Primary Examiner — David Muller

CLAIM

The ornamental design for a toxicology cup, as shown and described.

DESCRIPTION

FIG. 1 is a perspective view of the claimed design for a toxicology cup;

FIG. 2 is a bottom perspective view

FIG. 3 is a front plan view thereof;

FIG. 4 is a bottom plan view thereof;

FIG. 5 is a rear plan view thereof;

FIG. 6 is a top view thereof;

FIG. 7 is a right side view thereof;

FIG. 8 is a left view thereof; and,

FIG. 9 is a perspective view thereof showing an example lid. The features shown in broken lines depict environmental structure only and form no part of the claimed design.
